UNITED STATES PATENT OFFICE.

THELUS M. BISSELL, OF SOUTH BEND, INDIANA.

BOLT FOR CHILLED PLOWS.

SPECIFICATION forming part of Letters Patent No. 256,275, dated April 11, 1882.

Application filed December 29, 1881. (No model.)

To all whom it may concern:

Be it known that I, THELUS M. BISSELL, of South Bend, in the county of St. Joseph and State of Indiana, have invented certain new and useful Improvements in Bolts for Chilled Plows; and I do hereby declare that the following is a full, clear, and exact description thereof, reference being had to the accompanying drawings, and to the letters of reference marked thereon, which form part of this specification, in which—

Figure 1 is a perspective view of my bolt. Fig. 2 is a central vertical section of the same; and Fig. 3 is a view of part of a mold-board with bolt-holes adapted to receive these bolts.

The special object I have in view is to provide means whereby the chilled mold-boards of chilled plows may be more thoroughly and satisfactorily fastened than has hitherto been done. The difficulties which are avoided by my invention are such as have been keenly felt by manufacturers of chilled plows, as the holes in chilled mold-boards have to be cast with curved surfaces, otherwise they will check from their corners in cooling, and thus not only mar the appearance of the board, but also impair its operation. If the holes are cast round, the bolt, which must also be round, will turn, and the head will present its edge, thus roughening the surface of the mold-board and prevent the perfect scouring of the plow; and, again, as the head wears away it loses its gripe—that is, the flare is not sufficient to keep the mold-board solidly to its place. When the shaft of the bolt is made square it is apt to break the casting through which it passes. All of the aforesaid difficulties are obviated by constructing a bolt as I will now proceed to describe.

40 A represents my bolt, consisting of the uniformly-round shaft *a*, provided with screw-thread *b*, and oblong conical head *c*, with shoulder *d*. It will thus be observed that while I

am enabled to retain the curved surface of the hole in the mold-board by the formation of my 45 bolt, I adequately provide for the difficulties consequent upon the use of the ordinary round bolt as the oblong head will prevent it turning, and the conical surface will admit of so casting the holes in the mold-board as will 50 avoid checking in casting or cooling, while the shoulders will always wear smoothly with the mold-board, and yet contain metal sufficient to hold firmly.

Another advantage of my bolt is that the 55 shaft may be made small enough to pass through the lighter castings on the under side of the mold-board.

I am aware that there have been used with chilled mold-boards bolts with conical circular 60 heads having a shoulder, and bolts having oval heads without a shoulder, as well as bolts having conical circular heads without a shoulder, and do not wish to be understood as claiming such as my invention; but

65 What I do claim, and desire to secure by Letters Patent, is—

1. A bolt formed as herein described—that is to say, with a round shaft of uniform diameter, having at one end a screw-thread and at 70 the other a shouldered oblong conical head, all substantially as set forth.

2. The combination, with a chilled mold-board provided with oval apertures, of a bolt constructed with a shaft of uniform diameter, 75 having a screw-thread at one end and a shouldered oblong conical head at the other, all as herein described and shown.

In testimony that I claim the foregoing as my own I affix my signature in presence of two 80 witnesses.

THELUS M. BISSELL.
